LOCOMOTIVE TENDER

Charles J. Surdykowski, Tuckahoe, N. Y., now by judicial change of name Charles J. Surdy, assignor to Standard Stoker Company, Inc., a corporation of Delaware

Application November 23, 1932, Serial No. 643,973
Renewed July 5, 1935

15 Claims. (Cl. 198—15)

This invention relates to railway rolling stock and more particularly to certain improvements in locomotive tenders for stoker fired locomotives, and it also appertains to improvements in a 5 stoker fuel conveyor for use with such an improved tender.

It is the principal object of this invention to construct a tender for stoker fired locomotives, the tender conveying unit being driven from its 10 forward end and the locomotive unit of the stoker being driven from its rearward end, such driving means arranged to be received in the conventional compartment usually provided for this purpose and being disposed wholly below the fuel bin floor 15 and the shovelling deck of the tender.

In carrying out the principal object of this invention, the adjacent ends of the stoker conveying system are offset laterally and vertically in a manner to reduce the vertical distance between 20 the two conveying sections. Such lateral disposal of these sections, necessitates in certain cases, that the axis of the conveyor which underlies the fuel bin be offset laterally from the longitudinal center line of the tender, and accordingly, this 25 forms another object of this invention.

These and other objects of this invention will become apparent as the following description is read in connection with the accompanying drawings in which

30 Figure 1 is a central vertical longitudinal section through the tender conveying unit of a stoker as applied to locomotive tenders;

Figure 2 is a section taken on the line 2—2 of Figure 1;

35 Figure 3 is a section taken on the line 3—3 of Figure 1;

Figure 4 is a section taken on the line 4—4 of Figure 1;

Figure 5 is a section taken on the line 5—5 of Figure 4; and

Figure 6 is a view similar to Figure 2 showing a modified form of the invention.

On the drawings, the tender is indicated by A, and comprises the water compartment W and the 45 fuel bin F which is mounted above the floor 10, the forward continuation of which constitutes the shovelling deck 11. The floor 10 is apertured as at 12 and a plurality of shiftable plates 13 control the size of the aperture whereby varying amounts 50 of fuel may be fed from the bin F into the trough 14 mounted beneath the fuel bin floor 10. The trough 14 is disposed within the water compartment W and is supported from the base frame 15 by the legs such as 16. At its forward end, 55 the trough 14 extends from within the water

compartment into an alcove 17 which is separated from the water compartment W by the rear wall 18 and the side walls 18a and 18b, formed integral with the trough 14. While the construction thus far described has emphasized 5 the fact that the trough 14 is disposed within the water compartment, the present invention is not limited to use with the trough so disposed but is capable of advantageous use in such instances where a front drive for the stoker trough 10 is desired.

A conveyor screw 19 is mounted in the trough 14 and is driven from its forward end by suitable gearing housed in the gear case 20. This gearing comprises a pinion 21, which is driven from any 15 suitable source through the coupling member 22 (Figure 4) and meshes with a gear 23 mounted on a shaft 24 which is in driving connection with the conveyor screw 19. The screw 19 urges fuel forwardly past the crusher 25 which reduces the 20 fuel to a size suitable for firing. The crushed fuel then drops into the conduit 26 which is disposed below the trough 14 and laterally thereof. A chute 27 connects the forward end portion of 25 the trough 14 and the conduit 26. While the conduit 26 is shown as being formed integral with the trough 14, obviously, it could also be made as a separable unit rigidly attached to the base frame 15 of the tender.

Mounted in the conduit 26 is a conveyor screw 30 28 which is connected universally as at 29 to the screw 30 housed in the tubular section 31. The tubular section 31 is flexibly connected as at 32 to the forward end of the conduit 26 and leads forwardly to the locomotive for delivering fuel into 35 the firebox. As the rear of the conduit 26 is a gear case 33 which houses a gear 34 mounted on an extension of the screw 28 whereby motion is transmitted thereto. The gear 34 is meshed by a pinion 35 mounted on a jack shaft 36 which 40 underlies the forward portion of the trough 14 and extends into the gear case 20. A gear 37 is mounted on the opposite end of the jack shaft 36 and is driven by the gear 23, thereby completing 45 the train of gears for operating the screws 19 and 28. It will be observed from the drawings that by offsetting the conduit 26 laterally below the trough 14, the gearing for driving the stoker screws is compactly disposed within the limits 50 of the compartment or alcove 17.

Usually, the locomotive unit of the stoker, termed the discharge conduit is disposed on the longitudinal center line of the locomotive and tender, and it has been customary to similarly 55

dispose the remaining connected conduits of the conveying system. This being necessary so that there will not be an initial angularity between these conduits when the locomotive and tender 5 are on a straight track. It will be readily understood that if the conduits were disposed angularly when on a straight track, this condition would be greatly aggravated when the locomotive and tender are negotiating curves. Such a condition would result in rapid wear upon the conduit joints due to the strains and stress imposed thereupon and would necessitate a frequent renewal of these parts.

Accordingly, since the conduit 26 is disposed laterally of the trough 14, I prefer that the axis 15 of this conduit remain on the longitudinal center line of the locomotive and tender, and instead I dispose the axis of the trough 14 to the right or left of this center line, as the case may be, a 20 distance equal to the lateral offset between the conduit 26 and the trough 14. The aperture 12, is likewise offset and the side slope sheets 40 and 41 of the fuel bin are preferably terminated at the marginal edge of this aperture, thereby forming 25 a fuel bin which is self cleaning.

On Figure 6, which illustrates a modified form of the invention, the axis of the trough 14a is disposed on the longitudinal center line of the tender, while the axis of the conduit 26a is offset 30 laterally therefrom. Such a construction can be used advantageously in those instances where the tubular section leading from the tender is connected to the discharge conduit at a point offset laterally from the center line of the locomotive, 35 or, in such cases where rail curves are so slight that an initial angularity of the conduits is not objectionable. In all its other details, this form of the invention is similar to the preferred form.

While I have illustrated and described two forms 40 of my invention, I contemplate the use of my invention to the extent of offsetting each of the conduits 14 and 26 from the center line of the locomotive and tender. Structures of such scope I have included within the terms of the following 45 claims.

I claim:

1. In a locomotive tender including a base frame, an apertured floor above said frame forming a shovelling deck for said tender, a fuel bin 50 mounted above said apertured floor, a stoker trough mounted beneath said apertured floor and arranged to receive fuel from said bin, the axis of said trough being disposed to one side of the longitudinal center line of the tender, and a conduit receiving fuel from said trough having its 55 axis disposed on the longitudinal center line of the tender below the axis of said trough.

2. In a locomotive tender including a base frame, an apertured floor above said frame forming a shovelling deck for said tender, a fuel bin mounted above said apertured floor, a stoker trough mounted beneath said apertured floor and arranged to receive fuel from said bin, the axis 60 of said trough being disposed to one side of the longitudinal center line of the tender, a conveyor in said trough, means for driving said conveyor from its forward end, a conduit receiving fuel from said trough and having its axis disposed on the longitudinal center line of the 65 tender below the axis of said trough, a conveyor in said conduit, and means at the rear of said conduit for driving said conveyor.

3. In a locomotive tender including a base frame, an apertured floor above said frame comprising a shovelling deck for said apertured floor,

a stoker trough mounted beneath said apertured floor and arranged to receive fuel from said bin, the axis of said trough being disposed to one side of the longitudinal center line of the tender, a conveyor screw in said trough, gearing at the forward end of the trough for driving said screw, a conduit receiving fuel from said trough and having its axis disposed on the longitudinal center line of the tender, a conveyor screw in said conduit, and gearing at the rear of said conduit for driving the conveyor screw therein. 10

4. In a locomotive tender including a base frame, an apertured floor above said frame comprising a shovelling deck for said tender, a fuel bin mounted above said floor, a stoker trough mounted beneath said apertured floor and arranged to receive fuel from said bin, a conveyor screw in said trough, a gear case at the forward end of and carried by said trough, gearing in said gear case for driving said conveyor screw, a conduit receiving fuel from said trough and having its axis disposed laterally of and below the axis of said trough, a conveyor screw in said conduit, a gear case at the rear of said conduit, gearing in said gear case for driving said conveyor screw in said conduit, and a shaft connecting the first and second named gearing. 15

5. In a locomotive tender including a base frame, an apertured floor above said frame comprising a shovelling deck for said tender, a stoker trough mounted beneath said apertured floor and arranged to receive fuel from said bin, the axis of said trough being disposed to one side of the longitudinal center line of the tender, a conveyor screw in said trough, a gear case at the forward end of said trough, gearing in said gear case for driving said conveyor screw, a conduit receiving fuel from said trough and having its axis on the longitudinal center line of the tender, a conveyor screw in said conduit, a gear case at the rear of said conduit, gearing in said gear case for driving the conveyor screw in said conduit, and a shaft connecting the first and second named gearing. 30

6. In a locomotive tender including a base frame, an apertured floor above said frame comprising a shovelling deck for said tender, a fuel bin mounted above said apertured floor, a stoker trough mounted beneath said apertured floor and arranged to receive fuel from said bin, a conveyor screw in said trough, a gear case at the forward end of and carried by said trough, gearing in said gear case for driving said conveyor screw, a conduit disposed below said trough receiving fuel from the forward end of said trough, a conveyor screw in said conduit, the fuel receiving end of said conveyor screw being disposed laterally of the forward end of the trough, a gear case at the rear of said conduit, gearing in said gear case for driving the conveyor screw in said conduit, and a shaft connecting the first and second named gearing. 45

7. In combination with a locomotive tender, a stoker including a screw conveyor on the tender, a gear drive on the tender forward of said conveyor driving the same from its forward end, a second screw conveyor communicating with said first named screw conveyor and having its rearward end disposed in a plane below and offset laterally to one side of the forward end of said first named screw conveyor, a gear drive 50 disposed rearward of said second named screw conveyor and for driving the same from its rearward end, a power shaft operatively associated with one of said gear drives and a jack shaft 55 interposed between and associated with the first 60

and second named gear drives for transferring motion from one to the other.

8. In a locomotive tender including a base frame, an apertured floor above said frame forming a deck for said tender, a fuel bin above said apertured floor, a stoker trough mounted beneath said apertured floor and arranged to receive fuel from said bin, the fuel delivery end of said trough being offset to one side of the vertical medial plane of the tender, and a conduit mounted on said tender receiving fuel from the delivery end of said trough and extending forwardly therefrom, the receiving end of such conduit being offset laterally from said trough.

15 9. In a locomotive tender including a base frame, an apertured floor above said frame forming a deck for said tender, a fuel bin above said apertured floor, a stoker trough mounted beneath said apertured floor and arranged to receive fuel from said bin, a conveyor screw in said trough, the delivery end of said conveyor screw being offset to one side of the vertical medial plane of the tender, a conduit mounted on said tender receiving fuel from the delivery end of said trough and extending forwardly therefrom, and a conveyor screw in said conduit, the fuel receiving end of such conveyor screw being offset laterally from the delivery end of the first named conveyor screw.

30 10. In a locomotive tender including a base frame, an apertured floor above said frame forming a deck for said tender, a fuel bin above said apertured floor, a stoker trough mounted beneath said apertured floor and arranged to receive fuel from said bin, the fuel delivery end of said trough being offset to one side of the vertical medial plane of the tender, and a conduit mounted on said tender receiving fuel from the delivery end of said trough and extending forwardly therefrom, the receiving end of such conduit being offset laterally from said trough and being disposed between the vertical medial plane of said trough and the side of said tender remote from the aforesaid vertical medial plane of said trough.

11. In a locomotive tender including a base frame, an apertured floor above said frame forming a deck for said tender, a fuel bin above said apertured floor, a stoker trough mounted beneath said apertured floor and arranged to receive fuel from said bin, a conveyor screw in said trough, the fuel delivery end of said conveyor screw being offset to one side of the vertical medial plane of the tender, a conduit mounted on said tender receiving fuel from the delivery end of said trough and extending forwardly therefrom, and a conveyor screw in said conduit, the fuel receiving end of such conveyor screw being arranged with its axis offset laterally from

the axis of the delivery end of said first named screw and being disposed between the vertical medial plane of said trough and the side of said tender remote from the aforesaid vertical medial plane of said trough.

5 12. In a locomotive tender including a base frame, an apertured floor above said frame forming a deck for said tender, a fuel bin mounted above said apertured floor, a stoker trough mounted beneath said bin to receive fuel therefrom and arranged to deliver the fuel at one side of the vertical medial plane of said tender, and a conduit mounted on the tender to receive fuel from said trough, the receiving end of such conduit being offset laterally from said trough.

10 13. In a locomotive tender including a base frame, an apertured floor above said frame forming a deck for said tender, a fuel bin mounted above said apertured floor, a stoker trough mounted beneath said bin to receive fuel therefrom and arranged to deliver the fuel at one side of the vertical medial plane of said tender, and a conduit mounted on the tender to receive fuel from said trough, the receiving end of such conduit being offset laterally from said trough and being disposed between the vertical medial plane of said trough and the side of the tender remote from the aforesaid vertical medial plane of said trough.

15 14. In a locomotive tender including a base frame, an apertured floor above said frame forming a deck for said tender, a fuel bin mounted above said apertured floor, a stoker trough mounted beneath said bin to receive fuel therefrom and arranged to deliver the fuel at one side of the vertical medial plane of said tender, and a conduit mounted on the tender to receive fuel from said trough, the receiving end of such conduit being offset laterally from said trough and extending forwardly therefrom, the forward end of said conduit being provided with one element of a flexible joint connection.

20 15. In a locomotive tender including a base frame, an apertured floor above said frame forming a deck for said tender, a fuel bin mounted above said apertured floor, a stoker trough mounted beneath said bin to receive fuel therefrom and arranged to deliver the fuel at one side of the vertical medial plane of said tender, and a conduit mounted on the tender to receive fuel from said trough, the receiving end of such conduit being offset laterally from said trough and extending forwardly therefrom, the forward end of said conduit being provided 25 with one element of a flexible joint disposed in the vertical medial plane of the tender.

CHARLES J. SURDYKOWSKI.
